DESIGN FOR A PENCIL

William S. Deree and Albert L. Coulter,
Chicago, Ill.

Application December 18, 1945, Serial No. 124,819

Term of patent 14 years

(Cl. D74—24)

To all whom it may concern:

Be it known that we, William S. Deree and Albert L. Coulter, citizens of the United States, residing at Chicago, in the county of Cook and State of Illinois, have invented a new, original, and ornamental Design for Pencils, of which the following is a specification, reference being had to the accompanying drawing, forming part thereof.

Fig. 1 is a side elevational view of a pencil, showing our new design;

Fig. 2 is a front end view; and

Fig. 3 is a rear end view.

We claim:

The ornamental design for a pencil, as shown.

WILLIAM S. DERE. ALBERT L. COULTER.
